PUMP PRIMING MEANS

Henry R. Welby, Detroit, Mich., assignor to Detroit Lubricator Company, Detroit, Mich., a corporation of Michigan

Application August 30, 1946, Serial No. 694,051

7 Claims. (Cl. 103—203)

1

This invention relates to new and useful improvements in pumps and more particularly to automatically operable means for eliminating air or gas binding of reciprocating pumps.

An object of the invention is to provide means operable by the pump piston for opening the pump discharge valve.

Another object is to provide a novel valve structure for cooperation with and opening movement by a pump piston.

The invention consists in the novel construction and cooperative arrangement of parts to be more fully described hereinafter and the novelty of which will be particularly pointed out and distinctly claimed.

In the accompanying drawings, to be taken as a part of this specification, there is fully and clearly illustrated a preferred embodiment of the invention, in which drawings:

Figure 1 is a view in vertical section of a pump and its discharge valve operating means together with the pump driving mechanism, and

Fig. 2 is an enlarged detail view in section showing the valve operating means in an actuated position.

Referring to the drawings by characters of reference, the numeral 1 designates the tank or casing of a force feed lubricator having a cover member 2 with a filling opening 3. Secured to the underside of the cover member 2, there is a pump having a casing 4 containing a flow chamber 5 which is intersected adjacent one end by a pump cylinder or chamber 6 in which a piston or plunger 7 is longitudinally reciprocal. The piston pumping end 8 projects into the chamber 5 during the final part of the compression or discharge stroke. The piston 7 is reciprocated by a lever 9 journaled on a shaft 10 and having an end portion 11 seating against the end faces of a piston slot 12. The lever 9 is oscillated by a yoke 13 journaled on the shaft 10 and driven by an eccentric 14. The yoke 13 has an adjustable abutment screw 15 cooperable with a shoulder 16 on the lever 9 to determine the length of the piston working stroke.

The pump casing 4 extends downward into an oil reservoir 17 and has an inlet passage 18 aligned with and leading to the chamber 5. A strainer 19 protects the inlet end of the passage 18 which has a pair of inlet valve ports controlled by ball type check valves 20, 21. At the outlet end of the chamber 5, there is a cylindrical recess in which a tubular outlet valve casing 22 slidably fits and is locked in position by a threaded sleeve 23. The casing 22 has an internal annular valve

2

seat 24 providing an outlet port normally closed by a spring-pressed check valve 25, preferably a ball valve member, urged to its seat by a coil spring 26 held under compression by a collar 27 press-fitted into the valve casing bore. On the inlet side of and concentric with the seat 24, there is an annular supporting member or bearing plate 28 which is locked in position by a metal ring 29. The plate 28 holds a sleeve 30 of tough 10 hard metal forming a wear or scuff plate in a recess concentric with and on the inlet side of the valve seat. Supported on the plate 28, there is a valve operating member 31, in the form of a rod or post, having a disk-like or circular head portion 32 which substantially fits within the sleeve 30, but with sufficient lateral play for free outflow of oil when lifted from the plate 28 as in Fig. 2. The head portion 32 is of a diameter such that upon rocking movement on its edge as a fulcrum, 20 it will have camming engagement with the inlet side of the ball check valve 25 and lift it to an open position as in Fig. 2. The lower end of the rod 31 extends into the chamber 5 and into the path of travel of the piston end portion 8 so that the rod 31 is rocked or pivoted on the plate 28 to open the valve 25 as the piston 7 completes its discharge stroke.

The operation of the pump is as follows: On each inward or discharge stroke of the piston 7, the end portion 8 will rock the rod 31 to force the valve 25 from its seat, overcoming the force of the spring 26. If any air or gas is trapped in the chamber 5, the opening of the valve 25 by the member 31 will permit its escape through the outlet passage 33 so that on the piston suction stroke, oil will be drawn in through the inlet passage 18. The opening of the valve 25 will also permit oil which may be in the outlet passage 33 to drain back into the chamber 5 thereby aiding the pump to regain its prime. In normal operation, the disk 32 will be lifted by the discharging oil before the rod 31 is rocked by the piston 7 so that rocking of the rod 31 will not be required to open the valve 25.

Having thus described my invention, what is claimed and is desired to be secured by Letters Patent of the United States is:

1. A pump comprising a casing having a cylinder and having a flow chamber intersected by said cylinder, a piston in said cylinder, said chamber having a valve controlled inlet port and having an outlet port, a check valve controlling said outlet port, and mechanical means engageable with said check valve and operable by said piston to move said check valve to open position,

2. A pump comprising a casing having a cylinder and having a flow chamber intersected by said cylinder, a piston in said cylinder, said chamber having a valve controlled inlet port and having an outlet port, a check valve controlling said outlet port, and means including a rockable member on the inlet side of and engageable with said check valve and operable by said piston to move said check valve to open position.

3. A pump comprising a casing having a cylinder and a flow chamber intersected by said cylinder, said chamber having a valve controlled inlet port and having an outlet port, a check valve controlling said outlet port, a piston in said cylinder and having an end portion movable into said chamber, a rod having an end portion operable upon rocking movement of said rod to move said check valve to open position, said rod extending into the path of movement of said piston for rocking movement thereby, and means supporting said rod for rocking movement.

4. A pump, comprising a casing having a cylinder and having a flow chamber intersected by said cylinder, said flow chamber having a valve controlled inlet port and having an open end, an outlet valve casing fitting in said chamber open end and having an internal annular valve seat; a spring-pressed check valve engageable with said seat, a piston reciprocal in said cylinder, and means carried by said valve casing and operable upon movement to engage and open said check valve, said means extending into the path of movement of said piston for engagement and movement thereby.

5. A pump, comprising a casing having a cylinder and having a flow chamber intersected by said cylinder, said flow chamber having a valve controlled inlet port and having an open end, an outlet valve casing fitting in said chamber open end and having an internal annular valve seat, a spring-pressed check valve engageable with said seat, a piston reciprocal in said cylinder and having an end portion movable into said chamber on the piston compression stroke, and a rockably supported rod carried by said valve casing and having one end portion extending into said chamber for engagement and rocking movement by said piston and having its other end portion engageable with said check valve and operable to open said check valve upon rocking movement.

6. A pump, comprising a casing having a cylinder and having a flow chamber intersected by said cylinder, said flow chamber having a valve controlled inlet port and having an open end, an outlet valve casing fitting in said chamber open end and having an internal annular valve seat, a spring-pressed check valve engageable with said seat, a piston reciprocal in said cylinder and having an end portion movable into said chamber on the piston compression stroke, and said valve casing having an annular supporting portion on the inlet side of said valve seat, and a rod extending through the central space of said supporting portion and having a head portion seating on said supporting portion, said head portion providing a fulcrum for rocking movement of said rod and being engageable with and operable to move to open position on rocking movement said check valve, said rod having an end portion extending into said chamber and into the path of movement of said piston, said rod end portion being so related to said piston as to be engaged and rocked by said piston during the end part of the piston compression stroke.

7. An outlet valve for a pump, comprising a tubular valve casing having an internal annular valve seat concentric with the casing bore; a valve member normally engaging said seat and movable therefrom by liquid pressure, an operating member in said casing bore on the inlet side of said valve member and having an end portion projecting from said casing, means in said bore supporting said operating member for rocking movement upon oscillation of said end portion, and means on said operating member engageable with and to open said valve member upon rocking movement of said operating member.
